MOTOR-STARTER.

1,149,136.

Specification of Letters Patent. Patented Aug. 3, 1915.

Original application filed June 16, 1913, Serial No. 773,874. Divided and this application filed May 4, 1914.
Serial No. 836,064.

To all whom it may concern:

Be it known that I, HARRY W. HAMILTON, a citizen of the United States, residing at Indianapolis, in the county of Marion and 5 State of Indiana, have invented a new and useful Motor-Start, of which the following is a specification.

It is the object of my invention to provide a simple and positive starter for internal 10 combustion engines, which shall act uniformly and without violence on the engine, requires the expenditure of a minimum amount of energy, is easily and inexpensively maintained, and is fool-proof.

15 In attaining this object, I provide two reservoirs one containing fluid under high pressure and the other fluid under relatively low pressure though materially higher than atmospheric pressure, connect said two reservoirs by an automatic pressure-reducing valve which closes when the pressure in the low pressure reservoir exceeds a predetermined value, and supply fluid from the low pressure reservoir through a suitable control 20 valve to start the engine by direct fluid pressure, by supplying it to a suitable auxiliary or starting motor, which may be connected to the engine by an automatic clutch acting to transmit power only from the auxiliary 25 motor to the engine. In addition there may be provided means for automatically closing the discharge from the low pressure reservoir when the pressure therein falls to a predetermined minimum, and also means 30 whereby the operation of the engine, when it is started, serves to restore the pressure in the low pressure reservoir, thus promoting economy in the use of fluid from the high pressure reservoir. The high pressure 35 reservoir, when discharged, may be recharged in any suitable manner, or a charged reservoir may be substituted for it.

The most suitable fluid for this use I have found to be carbon dioxid, as this fluid is 40 near its critical temperature at atmospheric temperatures, and, except in very hot weather, is partially liquefied under the pressure I use and so for any given tem-

perature a constant temperature is maintained in the high pressure reservoir as gas 50 is drawn therefrom so long as any carbon dioxid in the liquid state remains therein. I usually charge the high pressure reservoir so that if its contents be completely vaporized on account of hot weather the pressure 55 within the reservoir will be about fifteen hundred pounds, though at lower temperatures such pressure is lower than this because of the partial liquefaction.

This application is a division of my co- 60 pending application Serial No. 773,874, filed June 16, 1913.

The accompanying drawings illustrate my invention.

In these drawings, Figure 1 is a semi-diagrammatic view showing the system in its entirety and some of the parts in structural detail; and Fig. 2 is a fragmentary view showing a modification in which the gas pressure is normally maintained by a 70 separate pump operated by the engine.

Two reservoirs or storage tanks 10 and 11, for fluid under low and high pressure respectively, are connected through an automatic pressure-reducing valve 12, which conveniently is connected to the low pressure reservoir through a pipe 13 in which is a hand shut-off valve 14, and to the high pressure reservoir through a pipe 15 in which is a union or coupling 16 and a hand shut-off valve 17, the union or coupling allowing the high pressure reservoir readily to be disconnected and another one substituted for it. I have found carbon dioxid a most convenient fluid for this use, because it is partially liquefied at high pressure at most ordinary temperatures, its critical temperature being approximately 88.5° F.; and pressures of 150 and 1500 lbs. convenient pressures for the two reservoirs respectively, when the 90 temperature is so high that no liquefaction occurs, though the pressure in the high pressure cylinder will be lower than fifteen hundred pounds at any temperature below the critical temperature of carbon dioxid, because of the constant pressure which exists

in a partially liquefied gas at any given temperature. The automatic pressure-reducing valve 12 comprises a diaphragm 19 clamped between two casing sections 20 and 21, a 5 smaller diaphragm 22 clamped between the casing section 20 and a third casing section 23, a valve stem 24 which passes through the diaphragm 22 and is clamped thereto by clamping nuts 25 and is provided with a 10 head 26 which bears against that side of the diaphragm 19 which is toward the casing section 20, and an adjustable spring 27 which holds said head 26 against the diaphragm 19 and thus determines the pressure at which 15 the valve 12 opens or closes. The pipes 13 and 15 lead into the casing section 23 on the side of the diaphragm 22 remote from the diaphragm 19, the needle point on the valve stem 24 engaging its valve seat on the casing 20 section 23 when the diaphragm 19 is moved against the action of the spring 27. This movement of the diaphragm 19 is obtained by connecting the casing section 21 with the reservoir 10, as by means of a pipe 28 in 25 which may be located a hand shut-off valve 29. The pipe 28 and valve 29 need not be separate from the pipe 13 and the valve 14, though it is often convenient to have them so. The purpose of the diaphragm 22 is to 30 prevent the pressure in the reservoir 10 from acting against the side of the diaphragm 19 which is toward the casing section 20, said latter casing section being either closed or provided with vent openings 30.

35 As gas is drawn from the reservoir 10, and the pressure in such reservoir falls to a predetermined value, say 150 lbs., the spring 27 pushes the diaphragm 19 against the fluid pressure from the reservoir 10 and thereby 40 opens the automatic pressure-reducing valve, whereupon gas passes from the high pressure reservoir 11 through the valve 17, the pipe 15, the automatic pressure-reducing valve 12, the pipe 13, and the valve 14 to the 45 reservoir 10 to build up the pressure in the latter. When this pressure in the reservoir 10 rises to a predetermined value, say 160 lbs., it overcomes the action of the spring 27 on the diaphragm 19 and closes the automatic pressure-reducing valve. Thus the 50 pressure in the reservoir 10 is maintained substantially constant, and at a sufficiently low value, while the initial pressure in the reservoir 11 may be as high as desired.

55 The gas is drawn from the low pressure reservoir 10 for starting an internal combustion engine, as of an automobile, by direct fluid pressure. To this end, gas from the generator 10 is supplied through a pipe 60 35, which is preferably a branch pipe from the pipe 28 so that it may be controlled in common with the latter pipe by the hand shut-off valve 29, and an automatic cut-off valve to a supply pipe 36 leading to the engine through a hand control valve and, in

the arrangement shown in Fig. 1, a distributor, of which more hereafter. This automatic cut-off valve comprises casing sections 20' and 21', diaphragms 19' and 22', lock nuts 25', a head 26', and a spring 27' identical in structure with the parts 20, 21, 19, 22, 25, 26, and 27 already described. The valve stem 24' of the automatic cut-off valve differs from the valve stem 24 of the automatic pressure-reducing valve in that it has a flaring conical end 37 instead of a needle point, said flaring end 37 coöperating with a valve seat on a casing section 23' substantially identical with the casing section 23 save that the valve seat is on the side of the casing remote from the diaphragms. The pipes 35 and 36 are connected to the casing sections 23' in substantially the same manner as are the pipes 13 and 15 to the casing section 23 of the automatic pressure-reducing valve. 70 The automatic cut-off valve operates, in a manner exactly the reverse of that of the automatic pressure-reducing valve, to close the connection between the gas reservoir 10 and the pipe 36 when the pressure in such 80 reservoir falls below a predetermined valve, say 60 lbs., lower than that at which the automatic pressure-reducing valve opens. This prevents the operator from wasting the gas by continuing to draw it from the reservoir 10 when the pressure therein is too low to be efficient for starting the engine, and allows time, only a few minutes or even less ordinarily being necessary, for the pressure in the reservoir 10 to be built up by fluid 90 from the reservoir 11; then the automatic cut-off valve opens and allows gas to be drawn from the reservoir 10 to continue the starting operation. 95

The pipe 36 leads to the casing 40 of the control valve. This casing has a central passage 41 provided at its two ends with outwardly and oppositely facing valve seats, with which valve heads 42 and 43, which are mounted on a common valve stem 44 105 smaller than the passage 41 and are spaced farther apart than are the valve seats, respectively coöperative. The valve head 42 and its valve seat are conical, while the valve head 43 and its seat may be flat, the valve head 43 preferably being faced with rubber 110 45 or other yieldable material on its side toward the valve seat. The valve stem 44 of the control valve is suitably connected, as by a bell crank lever 46, to be moved by a rod 47 and push knob 48, the latter conveniently being mounted on the dash board of an automobile if the apparatus is used in connection with an automobile. The control valve is biased, both by a spring 49 and 120 by the pressure from the pipe 36 on the valve head 42, to hold said valve head against its seat and thus close the valve. When the knob 48 is pushed, the valve is opened by the separation of the valve head 42 from 125 130

its seat, the valve head 43 at the same time being moved against its valve seat to prevent leakage around the valve stem. The opening of the control valve opens the pipe 36 to a pipe 50, leading from the passage 41 between the two valve seats.

The pipe 50 leads from the discharge of the control valve to an auxiliary or starting motor 81. This motor 81 may be of any desired type, but is conveniently a rotary motor as shown; and it is conveniently mechanically connected by a suitable clutch 82, such as a roller clutch, to the shaft of the engine with which the device is associated, 15 a four-cylinder engine being illustrated. The clutch 82 is such that it will transmit power from the motor 81 to the engine to start the latter, but will not transmit power from the engine to the motor 81, thereby 20 allowing the latter to be at rest under normal conditions.

If desired, though it is not necessary, each of the engine cylinders 1, 2, 3, and 4 may be provided with a valve 55, which is normally closed but may be opened by the rod 47 when the latter is moved to open the control valve. The valves 55 may conveniently be of substantially the same structure as the control valve, with the opening at the 30 end of the valve casing connected to the interior of the cylinder and the opening at the side of the valve casing connected to the atmosphere. By having the valves 55 of this structure, any pressure from the 35 associated engine cylinder acts at all times against the head of the valve, thereby aiding the spring in keeping the valve seated and preventing leakage when the starter is not being operated to start the motor. However, the valves 55 may, if desired, take the form of ordinary pet cocks; or they may even be dispensed with entirely, though by using them the starting operation is facilitated. If desired, a shut-off valve 29', 45 separate from the valve 29, may be placed in the pipe 36, conveniently being located on the dash board if the device is used on an automobile.

In order to make the feeding of fluid from the high pressure reservoir 11 to the low pressure reservoir 10 a mere auxiliary action, and thus to promote economy, I provide other means for normally maintaining the gas pressure in said tank above the predetermined value at which the fluid from the reservoir 11 is admitted to the tank 10. In the arrangement shown in Fig. 1, this consists of a pipe 70 connecting the reservoir 10 and the engine cylinder 1, in which pipe 70, conveniently at the cylinder end thereof, is a check valve 71 which admits the passage of gas only from the reservoir, and even that only in case the pressure in the reservoir is below a predetermined value. 55 This predetermined value is somewhat

higher than that at which the automatic pressure-reducing valve opens. The check valve 71 may take various forms, but in the form illustrated comprises a body portion 72 provided with external heat-radiating 70 ribs 73 and with a central longitudinal opening 72' enlarged at the middle and smallest at the bottom and having a valve seat 74 between said middle and bottom portions, and a valve stem 75 movable in said opening and guided by the upper portion thereof and co-operating with said valve seat 74 to open and close the valve. The lower end of the opening in the valve body is connected to the cylinder 1 and the middle portion of 80 such opening to the reservoir 10 through the pipe 70. The valve stem 75 is provided with an opening 76 connecting the middle enlarged portion of the opening 72' with that portion of said opening which is above 85 the valve stem, so that the pressure from the reservoir 10 may act upon the top of the valve stem to assist in holding the valve closed.

With this arrangement the operation of 90 the engine causes the explosions in cylinder 1 to force part of the burned gases produced by such explosions through the check valve 71 and the pipe 70 into the reservoir 10 whenever the pressure in said tank is below 95 the predetermined value at which the check valve 71 may open. When the pressure in said reservoir equals or exceeds that value, the check valve 71 remains constantly closed.

Instead of using the burned gases from one of the engine cylinders for replenishing the reservoir 10, such replenishing may be obtained by a pump 78 driven from the engine shaft 59, as shown in Fig. 2; a clutch 78' may be included in the mechanical connection between the engine shaft 59 and the pump 78. Conveniently this pump 78 supplies air to the reservoir 10, though any other desired gas may be supplied. The connection from the pump 78 to the reservoir 10 is through a pipe 70', in which may be located a suitable check valve 79. When a predetermined pressure is reached in the reservoir 10, the reaction of such pressure on the pump causes the supply of gas from the latter to the reservoir to cease, or the clutch 78' may be disengaged.

To start the engine, the ignition circuit, if desired, first being closed as is usually done preparatory to cranking the engine, the 120 knob 48 is pushed to open the control valve and the valves 55. This admits pressure from the reservoir 10, provided such pressure is sufficiently high to allow the automatic cut-off valve to be open, through the pipe 50 to the auxiliary or starting motor 81. At the same time, the pressure within the engine cylinders is relieved by the opening of the valves 55, if such valves are used. The pressure thus supplied from the reser- 130

voir 10 to the auxiliary or starting motor 81 causes the latter to rotate, and this rotation is transmitted through the clutch 82 to the shaft of the engine. After a few revolutions of the engine shaft the knob 48 may be released to permit the spring 49 to close the valves 55 and the control valve. The ignition circuit must now be closed if it has not previously been closed. The engine is now in its normal condition and operates under its own power, the momentum given it by the starting carrying it past the point where the first explosion of compressed carbureted air takes place, just as in the case of cranking by hand. While the starter gas I preferably use is carbon-dioxid, which is not explosive, explosive or combustible gases may be used, as the starting operation involves no explosion.

20 When fluid has been drawn from the reservoir 10, and the pressure therein thus reduced, the subsequent operation of the engine, after it is started, serves by its pumping action through the check valve 71 or the pump 78 to build up such pressure again to normal, and thus to maintain it at its predetermined value without normally drawing the fluid from the high pressure reservoir 11. However, if for any reason this pump 25 action does not take place, as because of difficulty in starting the engine, or even because the means for replenishing the pressure by the engine operation is omitted, and the pressure in the reservoir 10 is reduced sufficiently low to allow the automatic pressure-reducing valve 12 to open, the pressure in the reservoir 10 is built up again by fluid from the reservoir 11. However, the pressure in the reservoir 11, if carbon dioxid is 30 the fluid used, does not change so long as its temperature remains constant and any of the carbon dioxid within the reservoir is in the liquid state. If too much gas is drawn from the reservoir 10 for any reason, 35 and the pressure therein is reduced below an efficient value for starting the engine, the automatic cut-off valve closes to give such pressure time to build up by fluid from the reservoir 11. As soon as the pressure is 40 built up, which as heretofore shown requires but little time, the automatic cut-off valve opens to allow the starting operation to continue. When the pressure in the high pressure reservoir 11 is exhausted, the union 45 or coupling 16 may be disconnected, the valves 14 and 17 first being closed, and the reservoir 11 recharged or a charged reservoir substituted for it.

I claim as my invention:

60 1. In combination, a high pressure reservoir, a low pressure reservoir, an automatic pressure-reducing valve through which said two reservoirs are connected, an internal combustion engine, a fluid-pressure mo-

tor, a clutch by which said fluid-pressure 65 motor is connected to said engine, said clutch transmitting power from the motor to the engine but not from the engine to the motor, a control valve for supplying fluid pressure from the low pressure reservoir to 70 said motor to operate it by direct fluid pressure, and an automatic cut-off valve for closing the discharge from the low pressure reservoir when the pressure therein falls to a predetermined minimum. 75

2. In combination, a high pressure reservoir, a low pressure reservoir, an automatic pressure-reducing valve through which said two reservoirs are connected, an internal combustion engine, a fluid-pressure motor, 80 a clutch by which said fluid-pressure motor is connected to said engine, said clutch transmitting power from the motor to the engine but not from the engine to the motor, a control valve for supplying fluid pressure 85 from the low pressure reservoir to said motor to operate it by direct fluid pressure, and means whereby the operation of the engine builds up the pressure in the low pressure reservoir to a predetermined value. 90

3. In combination, a high pressure reservoir, a low pressure reservoir, an automatic pressure-reducing valve through which said two reservoirs are connected, an internal combustion engine, a fluid-pressure motor, 95 a clutch by which said fluid-pressure motor is connected to said engine, a control valve for supplying fluid pressure from the low pressure reservoir to said motor to operate it by direct fluid pressure, and an automatic 100 cut-off valve for closing the discharge from the low pressure reservoir when the pressure therein falls to a predetermined minimum.

4. In combination, a high pressure reservoir, a low pressure reservoir, an automatic 105 pressure-reducing valve through which said two reservoirs are connected, an internal combustion engine, a fluid-pressure motor, a clutch by which said fluid-pressure motor is connected to said engine, a control valve 110 for supplying fluid pressure from the low pressure reservoir to said motor to operate it by direct fluid pressure, and means whereby the operation of the engine builds up the pressure in the low pressure reservoir to a 115 predetermined value.

5. In combination, a high pressure reservoir, a low pressure reservoir, an automatic pressure-reducing valve through which said two reservoirs are connected, an internal 120 combustion engine, a fluid-pressure motor connected to said engine, a control valve for supplying fluid pressure from the low pressure reservoir to said motor to operate it by direct fluid pressure, an automatic cut-off 125 valve for closing the discharge from the low pressure reservoir when the pressure therein falls to a predetermined minimum, and

- means whereby the operation of the engine builds up the pressure in the low pressure reservoir to a predetermined value.
6. In combination, a high pressure reservoir, a low pressure reservoir, an automatic pressure-reducing valve through which said two reservoirs are connected, an internal combustion engine, a fluid-pressure motor connected to said engine, a control valve for supplying fluid pressure from the low pressure reservoir to said motor to operate it by direct fluid pressure, and an automatic cut-off valve for closing the discharge from the low pressure reservoir when the pressure therein falls to a predetermined minimum.
7. In combination, a high pressure reservoir, a low pressure reservoir, an automatic pressure-reducing valve through which said two reservoirs are connected, an internal combustion engine, a fluid-pressure motor connected to said engine, a control valve for supplying fluid pressure from the low pressure reservoir to said motor to operate it by direct fluid pressure, and means whereby the operation of the engine builds up the pressure in the low pressure reservoir to a predetermined value.
8. In combination, an internal combustion engine, a fluid-pressure starting motor for said engine, a reservoir for gas under pressure, means for supplying gas from said reservoir to said starting motor to start said engine, means for replenishing the gas pressure in said reservoir by the operation of the engine after it is started, and means for automatically replenishing the gas pressure in said reservoir when it falls below a predetermined value which is lower than the value at which the pressure in said tank is normally kept by the engine operation.
9. In combination, an internal combustion engine, a fluid-pressure starting motor for said engine, a reservoir for gas under pressure, means for supplying gas from said reservoir to said starting motor to start said engine, means for replenishing the gas pressure in said reservoir by the operation of the engine after it is started, and means for automatically replenishing the gas pressure in said reservoir when it falls below a predetermined value.
10. In combination, an internal combustion engine, a fluid-pressure starting motor for said engine, a reservoir for gas under pressure, means for supplying gas from said reservoir to said starting motor to start said engine, means for automatically replenishing the gas pressure in said reservoir when it falls below a predetermined value, and an automatic cut-off valve for closing the connection whereby the gas is supplied from the reservoir in case the pressure in the reservoir falls below a lower predetermined value.
11. In combination, an internal combustion engine, a fluid-pressure starting motor for said engine, a reservoir for gas under pressure, means for supplying gas from said reservoir to said starting motor to start said engine, means for replenishing the gas pressure of said reservoir by the operation of the engine after it is started, means for automatically replenishing the gas pressure in said reservoir when it falls below a predetermined value which is lower than the value at which the pressure in said tank is normally kept by the engine operation, and an automatic cut-off valve for closing the connection whereby the gas is supplied from the reservoir in case the pressure in the reservoir falls below a still lower predetermined value.
12. In combination, an internal combustion engine, a fluid-pressure starting motor for said engine, a reservoir for gas under pressure, means for supplying gas from said reservoir to said starting motor to start said engine, means for replenishing the gas pressure of said reservoir by the operation of the engine after it is started, means for automatically replenishing the gas pressure in said reservoir when it falls below a predetermined value, and an automatic cut-off valve for closing the connection whereby the gas is supplied from the reservoir in case the pressure in the reservoir falls below a lower predetermined value.
13. In combination, an internal combustion engine, a fluid-pressure starting motor therefor, a reservoir for gas under pressure, a control valve for supplying gas from said reservoir to said starting motor to start said engine, an automatic valve responsive to the pressure in said reservoir for admitting material thereinto to replenish the gas pressure therein, and an automatic cut-off valve for closing the connection whereby the gas is supplied from the reservoir in case the pressure in the reservoir falls below a predetermined value.
14. In combination, an internal combustion engine, a fluid-pressure starting motor for said engine, a reservoir for gas under pressure, means for supplying gas from said reservoir to said starting motor to start said engine, means acting independently of the engine for automatically replenishing the gas pressure in said reservoir when it falls below a predetermined value, and an automatic cut-off valve for closing the connection whereby the gas is supplied from the reservoir in case the pressure in the reservoir falls below a lower predetermined value.
15. In combination, a high pressure reservoir, a low pressure reservoir, a valve through which said two reservoirs are connected, an internal combustion engine, a

fluid-pressure motor connected to said engine, a control valve for supplying fluid-pressure from the low pressure reservoir to said motor to operate it by direct fluid-pressure, and means for restoring the pressure in the low pressure reservoir independently of the high pressure reservoir.

In witness whereof, I, have hereunto set

my hand at Indianapolis, Indiana, this first day of May, A. D. one thousand nine hundred and thirteen.

HARRY W. HAMILTON.
